UNITED STATES PATENT OFFICE

169,490

COMBINED BOTTLE OPENER AND SCREW DRIVER

Christian J. Hug, Highland, Ill.

Application August 25, 1952, Serial No. 21,181

Term of patent 14 years

(Cl. D44—29)

To all whom it may concern:

Be it known that I, Christian J. Hug, a citizen of the United States, residing at Highland, Madison County, Illinois, have invented a new, original, and ornamental Design for a Combined Bottle Opener and Screw Driver, of which the following is a specification, reference being had to the accompanying drawing, forming a part hereof.

Fig. 1 is a top edge view of a bottle opener and screw driver embodying my new design;

Fig. 2 is a back view in elevation;

Fig. 3 is a bottom edge view; and

Fig. 4 is a front elevation.

I claim:

The ornamental design for a combined bottle opener and screw driver, as shown.

CHRISTIAN J. HUG.
